UNITED STATES PATENT OFFICE.

HOMER L. BOYLE, OF LANSING, MICHIGAN, ASSIGNEE OF ONE-HALF TO SAMUEL H. DAVIS, OF LANSING, MICHIGAN.

VACUUM OR SUCTION SWEEPER.

1,124,997.

Specification of Letters Patent. Patented Jan. 12, 1915.

Application filed April 24, 1914. Serial No. 834,155.

To all whom it may concern:

Be it known that I, HOMER L. BOYLE, a citizen of the United States, residing at Lansing, in the county of Ingham and State 5 of Michigan, have invented certain new and useful Improvements in Vacuum or Suction Sweepers, of which the following is a specification.

My invention relates to improvements in 10 vacuum or suction sweepers and more particularly to vacuum cleaners having parts of special construction and arrangement with respect to each other, and comprising a bellows having its boards provided with 15 extension members rigidly secured to the boards.

This invention has an operating handle or stick similar to a broomstick, and one 20 of the arms is rigidly connected with the handle, while the other arm is pivotally secured to the handle. One bellows board is, therefore, fixed and the other movable with 25 respect to the handle. The object of providing the arms as hereinafter shown and described is to allow a considerable movement of the movable board, thus permitting the boards to be widely separated and correspondingly increasing the capacity of the 30 bellows without making the boards of unwieldy size. A further reason for extending the movement of the movable board of the bellows is that this invention is operated by the same sweeping movement given to an ordinary broom, and it is de- 35 sired that the opening or dust-sucking action of the bellows shall continue as nearly as practicable during the sweeping stroke. The closing of the bellows is effected by 40 a spring, and the dust laden air is forced into a dust sack of porous fabric through which the air passes, leaving the dust in the sack.

The special construction and arrangement comprising this invention is illustrated in 45 the accompanying drawings, of which—

Figure 1 represents a rear view with the dust sack removed. Fig. 2 is a front view. Fig. 3 is a vertical section on the broken line $x-x$ of Fig. 1, showing the bellows closed. Fig. 4 is a side view showing the bellows extended. Fig. 5 is a rear view of 50 a modified form of this invention with the dust sack removed. Fig. 6 is a front view of the same modification. Fig. 7 is a ver-

tical section of the same modification with 55 the dust sack removed, the section being taken on the broken line $y-y$ of Fig. 5. Fig. 8 is an enlarged vertical section of the lower part of the nozzle of the modification. In Figs. 1 to 7, inclusively, the handle is 60 shown broken off, and in all the figures the same letter refers to the same part.

Considering Figs. 1, 2, 3 and 4, of the drawings, the handle A has a socket B within which its lower end is secured, and 65 the extension pieces or arms C and C' that are rigidly attached to the bellows boards D and D', lead upwardly to the socket. Bands E and E' are employed to secure the bellows cloth or leather peripherally upon 70 the edges of the bellows boards, which, in practice are usually circular as illustrated.

The letter F designates an annular projecting portion upon the board D'. It is 75 the dust sack connection, and will be again mentioned.

The letters G and G' refer, respectively, to the valve controlling the entrance for the 80 dust and air into the bellows from the nozzle H, and the outlet from the bellows into the dust sack. A pivot pin I connects the arm C with the socket B, while the arm C' is rigidly attached to the socket.

Through the lower end of the socket B the bolt J, best shown in Figs. 3 and 4, ex- 85 tends transversely between the arms C and C'. The bolt also passes through the cross bar K, shown in Figs. 2 and 3, and connecting the upper parts of the arm C, and the head of the bolt rests against the outside of 90 the cross bar. A coil spring L encircles the bolt J and is confined between the washer on the bolt and the inside of the socket B. The bellows M is arranged between the bellows boards in the customary manner, and 95 the dust sack N is connected with the annular portion F that projects from the bellows board D'.

The operation of the preferred form of 100 this invention described, may be explained as below set forth.

It is believed to be clear from the foregoing that the arm C, bellows board D and nozzle H, are movable with respect to the handle and the other board D'. If now the 105 mouth of the nozzle H be placed in contact with the floor of a room, and this invention is given a sweeping movement, the washer

on the bolt J will compress the spring L, because the bolt engages the bar K forming a part of the arm C, and the end of the spring L rests against the inside of the lower portion of the socket B as shown in Figs. 3 and 4. The bellows M will now become extended into the position illustrated in Fig. 4, the opening of the bellows taking place during the sweeping stroke, thus charging 10 the bellows with dust and dirt sucked in with the air. When the sweeping stroke is ended, this invention is raised in order to begin another sweeping stroke, and the spring L closes the bellows, driving the air and dust into the dust sack N, through the fabric of which the air passes sifting out the dirt and leaving it within the sack. The neck of the dust sack N is secured to the bellows by means of the annular projecting 15 portion F.

In the modification of this invention set forth in Figs. 5, 6, 7, and 8, the handle A', the socket B' and the arm C², are the same as before, but the arm C³ is given a substantially circular form against the bellows board to add to the strength of the board. The bellows boards are marked D² and D³, and bands E² and E³ hold the bellows cloth or leather on the boards as before. The letter F designates the dust sack connection, and the letters G² and G³ the inlet and outlet valves. The nozzle is referred to by the letter H', and the pivot pin I' secures the arm C² pivotally to the socket B'. The 25 spring L' is connected directly with the arms C² and C³ by means of pins K' and K², as shown in Fig. 7. The bellows is referred to by the letter M'. The circular portion of the arm C³ is secured to the bellows board D³ by means of small ears riveted to the board as set out in Fig. 5.

In the modification shown in the Figs. 5, 6, 7, and 8, and as best illustrated in Figs. 5 and 7, the board D³ has a removable center piece R, that carries the dust sack connection F' and the outlet valve G³. This board bears also the screen V, and, if desired, the usual dust sack may be dispensed with, and the dust and dirt will accumulate 30 within the bellows M', from which it may be readily cleaned out by the removal of the center piece or board R. The board R is held in its place by the pivoted wire loop r, which is turned down upon the outside of

the piece R and fastened by a catch W, as shown in Fig. 5.

In the modification just described, the mouth of the passage O' of the nozzle H' may be provided with a covering, comprising a bendable metal plate T coated with 60 a compressible fabric U, in order that the mouth of the nozzle may be pressed into air tight contact with a carpet to be cleansed, and, incidentally, the pressure and movement will wear away the removable cover 65 and not the actual end of the nozzle. To secure the cover U the plate T has its edges bent around the bead of the nozzle, H' as best shown in Fig. 8.

Having described and explained my invention, I claim:

1. In a vacuum sweeper, the combination with a handle, of a bellows having bellows boards, arms having their lower ends rigidly attached to the said boards, one of the 75 said arms having its upper end rigidly connected with the said handle, and the other arm having its upper end pivotally connected with the said handle whereby one of the bellows boards is movable and one is 80 immovable with respect to the handle, a nozzle connected with the said movable board, an inlet valve controlling the passage in the nozzle, an outlet valve borne by the said immovable board, and removable 85 dust-screening means located adjacent to the said outlet valve and supported by the said immovable board.

2. In a vacuum sweeper, the combination with a handle, of a bellows having bellows 90 boards, arms having their lower ends rigidly attached to the said boards, one of the said arms having its upper end rigidly connected with the said handle, and the other arm having its upper end pivotally connected with the said handle whereby one of the bellows boards is movable and one is 95 immovable with respect to the handle, a nozzle connected with the said movable board, an inlet valve controlling the passage in the nozzle, a dust sack connection borne by said immovable board, and an outlet valve in the said connection. 100

HOMER L. BOYLE.
